Primary Examiner—Martie K. Holtje

(74) Attorney, Agent, or Firm—Standley & Gilcrest LLP

(57) **CLAIM**

The ornamental design for a millennium calendar, as shown and described.

DESCRIPTION

FIG. 1 is a front elevational view of the calendar of the present invention;

FIG. 2 is an enlarged view of a section of the calendar as indicated on FIG. 1;

FIG. 3 is an enlarged view of a section of the calendar as indicated on FIG. 1; and,

FIG. 4 is an enlarged view of a section of the calendar as indicated on FIG. 1.

The undisclosed rear surface is conventionally flat and unornamented.
